UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY OF PENNSYLVANIA,
OF SAME PLACE.

DESIGN FOR A SAD-IRON.

SPECIFICATION forming part of Design No. 22,811, dated September 26, 1893.

Application filed June 15, 1892. Serial No. 436,862. Term of patent 14 years.

To all whom it may concern:

Be it known that I, JOHN WILSON BROWN, Jr., a citizen of the United States, and a resident of Philadelphia, Pennsylvania, have invented a new and original Design for a Sad-Iron, of which the following is a specification.

My design is used with the Mary Potts sad-iron in which the base M of the sad-iron is curved at each side, terminating in sharp edges *m* at both ends, giving the double pointed or boat shape appearance.

The essential features of my design are the inclined edges *n* extending upwardly to a point midway between the ends, presenting

in side view a pentagonal form, and with *kk* curved enlargements on the top of the sad-iron extending transversely from a point near the center of the inclined sides or edges.

What I claim is—

The design for a sad-iron, substantially as herein described and shown.

In testimony whereof I have signed my name to this specification in the presence of two subscribing witnesses.

JOHN WILSON BROWN, JR.
